SPONGE UNDERLAY FOR CARPETS

William Perlman, Los Angeles, Calif.

Application December 13, 1955, Serial No. 39,313

Term of patent 14 years

(Cl. D92—4)

Fig. 1

Fig. 3

Fig. 1 is a plan view of a sponge underlay for carpets showing my new design.

Fig. 2 is a side elevational view of the same.

Fig. 3 is a perspective view showing the sponge underlay for carpets from one end.

I claim:

The ornamental design for a sponge underlay for carpets, substantially as shown.
